Original design application Mar. 11, 1971, Ser. No.
123,494, now Patent No. 288,141. Divided and this
application Dec. 13, 1972, Ser. No. 314,856

Term of patent 14 years

Int. Cl. D12—05; D8—99

U.S. Cl. D8—261

FIG. 1 is a top plan view of a poultry feeder chain embodying my new design.

FIG. 2 is a side elevation of the poultry feeder chain shown in FIG. 1.

FIG. 3 is a section taken at 3—3 in FIG. 2.

It is to be understood that the poultry feeder chain comprises repetitive lengths of links as shown in FIG. 1 and FIG. 2, the design illustrated by FIG. 3 being repeated in alternate links of the chain throughout its length.

This application is a division of my copending application Ser. No. 123,494, filed Mar. 11, 1971, now Pat. No. 288,141.

I claim:

The ornamental design for a poultry feeder chain, as shown and described.
